TRAY PACKAGE AND METHOD OF MAKING IT

Walton D. Lynch, Huntington, N.Y., assignor to Baljak Corporation, Wilmington, Del., a corporation of Delaware

Filed Oct. 9, 1958, Ser. No. 766,300

3 Claims. (Cl. 229—23)

This invention relates to improvements in the art of packaging and is more particularly directed to the packaging of a tray, such as an aluminum foil tray containing frozen food, in a folding box.

In the packaging of frozen foods, as well as certain other classes of merchandise, enclosing boxes are preferred which provide a positive lock after closing, in the sense that reopening of the box without structural damage to the box is difficult. A positive seal may be formed by means of adhesive, but the use of adhesive is awkward in that it complicates the closing machinery and is moreover attended by additional difficulties, if the box is made of paraffined board.

In the practice of the present invention mechanical tab locks are used, so that the use of adhesive may be dispensed with entirely.

Tab locks comprising a substantially T-shaped tab which is inserted into a slit in a wall panel are well-known in a variety of forms. The use of such tab locks involves certain difficulties arising from the necessity of inserting the tab into the locking cut or slit with a substantial force under which the panel containing the locking cut frequently yields, resulting either in infolding of the panel containing the cut or in an incomplete lock due to the fact that at the end of the closing motion the head of the T-tab has not yet engaged the panel containing the cut, the desired engagement being generally of the nature of an edge-to-panel engagement, the edge being a cut edge of the T-tab, and the panel being the one containing the cut or slit.

In the manual closing of boxes the dexterity of the operator may to a certain extent compensate for the aforesaid difficulties, but mechanical closing machines, which are required where large volumes of boxes are to be handled, perform a closing motion of a certain stroke which is not sufficient to produce a secure lock where the panel containing the cut yields, or where the locking tab is obstructed by the box contents with the result that the tab either buckles or curls.

The present invention provides a package as well as a method of forming the package which overcomes the aforementioned difficulties.

The objects, features and advantages of this invention will appear more fully from the detailed description which follows accompanied by drawings showing, for the purpose of illustration, a representative embodiment of the invention. The invention also resides in certain new and original features of construction and combination of elements, as well as steps and sequences of steps hereinafter set forth and claimed.

Although the characteristic features of this invention which are believed to be novel will be particularly pointed out in the claims appended hereto, the invention itself, its objects and advantages and the manner in which it may be carried out may be better understood by referring to the following description taken in connection with the accompanying drawings forming a part of it in which:

2

Fig. 1 is a plan view of a representative form of box blank which may be used in practicing the invention;

Figs. 2 to 7 illustrate perspectively a sequence of operations involved in the packaging of a tray in a box set up from the blank of Fig. 1; and

Fig. 8 is a sectional view of the resulting locked tray package.

In the following description and in the claims various details will be identified by specific names for convenience.

10 The names, however, are intended to be generic in their application. Corresponding reference characters refer to corresponding parts in the several figures of the drawings.

The drawings accompanying, and forming part of, this 15 specification disclose certain specific details of the invention for the purpose of explanation of its broader aspects, but it is understood that the invention may be modified in various respects without departure from the principles of the invention and that the invention may be applied 20 to other forms of boxes than the one shown.

The blank A shown in Fig. 1 is cut from suitable 25 foldable sheet material, such as paperboard, and comprises a first main, or bottom, panel 11 to which inner wall panels 12, 13, 14 and wall panel 15 are articulated along bottom fold lines 16, 17, 18 and 19.

A second main, or top, panel 20 is articulated to the 30 wall panel 15 along a top fold line 21, and outer wall panels 22, 23 and 24 are articulated to the top panel along top fold lines 25, 26 and 27.

35 The outer wall panels 22, 23 and 24 carry substantially T-shaped lock tabs 28 articulated to the respective panel along tab fold lines 29. Each lock tab has a reduced neck portion 30 across which the fold line 29 extends, and wing portion 31 extending beyond the ends of the 40 central portion 30.

The inner panels 12, 13 and 14 are provided with 45 internal locking cuts 32, each locking cut including a central cut portion 33 even-directed with the respective bottom fold line. The cut portion 33 may be in line 50 with respective bottom fold line or parallel thereto and somewhat spaced therefrom. The length of the central cut portion 33 is somewhat greater than the width of the neck portion 30, or the length of the tab fold line 29, but shorter than the width of the lock tabs 28 as measured from wing end 31 to wing end.

End portions 34 of the cuts 32 are curved away from the respective bottom fold line and extend from the central portion 33 of the cut into the body of the respective wall panel, thus forming 55 downwardly extending internal tongues 35 in the inner wall panels.

The forming of the box and the packaging of a tray or 60 similarly shaped article may proceed as shown in Figs. 2 to 7 as follows.

The tray T, shown empty in Figs. 3 and 4 for the 65 sake of clarity, is placed with its bottom panel 36 on the bottom panel 11 of the blank A. The bottom surface 36 of the tray occupies less space than the bottom panel 11 of the blank. The side walls 37 of the tray extend upwardly and flare outwardly and terminate at a rim 38 of approximately the same dimensions as the bottom panel 11 of the box.

The inner walls 12, 13 and 14 are folded upright 70 with respect to the bottom panel 11, as shown in Fig. 4, and bear in this position against the rim 38 of the tray which subsequently supports the inner wall panels against further inward movement. A substantially triangular space 39 remains between each inner wall panel, the tray wall 37 and the bottom panel. This space remains free and unobstructed for the subsequent insertion of 75 the lock tabs 28.

The top panel 20 is then folded over the tray, the outer wall panels 22, 23 and 24 are folded down and the look

tabs 28 are inserted into the respective locking cuts 32.

During the locking operation the inner side walls are firmly supported by the tray rim and do not yield, so that at the end of the locking operation, generally performed by a machine (not shown), the wing portion 31 of the lock tabs snap securely behind the inner wall panels into the space between the end portions 34 of the cuts and the respective bottom fold line.

The resulting lock is a secure one, and it is almost impossible to reopen the package without visual damage to the box.

Obviously the box may assume different forms and the tray may be inserted from the side, instead of the top, between the two main panels, whereafter the inner wall panels are folded against the tray rim and the locking procedure is carried out substantially as described.

What is claimed is:

1. A merchandise package comprising, a tray having a bottom and outwardly flared sides terminating at a rim extending, in plan view, beyond the boundaries of the tray bottom; and an enclosing box paperboard, said box comprising, a box bottom panel substantially equal in size to said rim, a rear panel articulated to said bottom panel, a cover panel articulated to said rear panel, and inner and outer wall panels articulated to said bottom panel and said top panel, respectively, said inner panels lying substantially in edge-to-surface abutment with said rim for support against infolding and having elongated apertures at the bottom, said apertures being formed by a cut in the shape of a shallow U having a central portion substantially coinciding with the line along which the respective panel is articulated to the bottom panel, and slanted end portions extending at an angle to the central portion; and substantially T-shaped lock tabs articulated to the said outer wall panels, said tabs extending through said apertures into the substantially triangular space between the tray sides, the box bottom and the inner panels.

2. A merchandise package comprising a tray having a bottom and outwardly flared sides terminating at a rim extending, in plan view, beyond the boundaries of the tray bottom; and an enclosing box of paperboard, said box comprising, two opposite main panels constituting the box bottom and the box top, respectively, said main panels being substantially equal in size to the tray measured at its rim; opposite inner and outer wall panels articulated to said bottom and said top, respectively, said inner panels lying substantially in edge-to-surface abutment with said rim for support against infolding, said inner panels having internal cuts in them, at least certain of said cuts including a central portion even-directed with the line along which the respective inner wall panel

is articulated to said bottom, and upwardly curved end portions extending from said central portion into the body of the respective inner wall panel, said cuts forming downwardly extending internal tongues in said inner wall panels; and lock tabs articulated to the said other wall panels, said lock tabs extending into the box through said cuts into the substantially triangular space between the respective outwardly flared tray side, the box bottom panel and the inner wall panels, said lock tabs comprising a central neck portion along which the tab is articulated to the respective outer wall panel, and wing portions extending beyond the ends of the central portion of the cuts in the inner wall panels and engaging the inner panels in edge-to-surface engagement, said internal tongues engaging said neck portion in an edge-to-surface engagement and urging said tabs against the bottom panel.

3. The method of packaging a tray having a bottom and upwardly and outwardly flared sides terminating at a rim in an enclosing folding box, the box blank comprising, two opposite main panels constituting the box bottom and the box top, respectively, said main panels being substantially equal in size to the tray measured at said rim; opposite inner and outer wall panels articulated to said bottom and said top, respectively, said inner panels having internal cuts in them, at least certain of said cuts having a central portion even-directed with the line along which the respective inner panel is articulated to said bottom, and upwardly curved end portions extending from said central portion into the body of the respective inner wall panel, said cuts forming downwardly extending internal tongues in said inner wall panels, and substantially T-shaped lock tabs articulated to the said outer panels, the method comprising, placing the tray bottom on said box bottom, folding said inner wall panels upright with respect to said bottom panel substantially into edge-to-surface abutting position with said rim constituting an inward stop for said inner wall panels, folding said outer panels to overlie said inner panels, and inserting said lock tabs through said cuts into the substantially triangular space between the tray side, the box bottom and the inner wall panel while inwardly supporting said inner panels by said rim against inward collapsing under the force incidental to the insertion of the lock tabs.
